UNITED STATES PATENT OFFICE.

ERNEST FREDERICK DURAND, OF PARIS, FRANCE, ASSIGNOR TO UNION SPECIAL SEWING MACHINE CO., OF CHICAGO, ILLINOIS, A CORPORATION OF ILLINOIS.

FEEDING MECHANISM FOR SEWING-MACHINES.

No. 901,792.

Specification of Letters Patent.

Patented Oct. 20, 1908.

Application filed April 1, 1901. Serial No. 53,826.

To all whom it may concern:

Be it known that I, ERNEST FREDERICK DURAND, a British subject, residing at Paris, Department of the Seine, Republic of France, have invented certain new and useful Improvements in Feeding Mechanism for Sewing-Machines, of which the following is a description, reference being had to the accompanying drawing, and to the letters and figures of reference marked thereon.

My invention relates to an improvement in sewing machines, and has especial reference to the feeding mechanism thereof, whereby in the uniting of two pieces of fabric, one may be fed faster than or slightly ahead of the other, so that it will be gathered, ruffled, or slightly crimped before the stitches are passed through the goods, an auxiliary feed, pivoted on the main rocking feed bar 20 and oscillated on its pivot in the movement thereof, being provided.

The particular object with which the improvement was designed, is for use in connection with the well known union special triple interlock machine, such as illustrated in the patent granted G. D. Munsing, October 10, 1893, No. 506,524, and patent granted L. Muther, October 10th, 1893, No. 506,527.

In the use of machines of this character for sewing ribbed fabric to plain fabric, as for instance, in sewing the cuffs of knit garments to the legs or arms thereof, considerable difficulty has been experienced by reason of the buckling of the ribbed fabric; for in attaching ribbed to plain fabrics, the rib has heretofore been stretched to the width of the plain fabric. This has given rise to the objection of puckering or buckling of the rib after the goods have been sewed, and I have devised a mechanism for ruffling or fulling in the plain fabric to meet the width of the ribbed fabric. In practice in sewing rib tails to garments, as for instance, on looping or turning off machines, it has been customary to place the plain fabric on the impaling pins and to stretch the ribbed fabric over the same.

In the use of my device, instead of stretching the ribbed fabric, it may be pulled in to meet the width of the plain fabric. In other words, I do not wish to be limited to the fulling in of any particular one of the two fabrics.

While the invention is herein illustrated as applied to what may be termed an over-

seaming machine, or a machine in which cross stitches are made, two fabrics whose edges are abutted being united by the stitches, substantially as shown in Fig. 5 of Patent 506,525, to G. D. Munsing, still I do not wish to be limited thus in its application, for so far as the main features are concerned, the invention may be used in connection with machines for ordinary straight away sewing, where two pieces of fabric are superposed or overlapped, instead of being merely abutted, in which event the lower or plain fabric may be ruffled or fulled in to equal in width the ribbed piece, and, therefore, so far as the mechanical features are concerned, I do not wish to be restricted to any particular type of sewing machine, or type of stitch forming mechanism.

The invention consists in the matters hereinafter described and referred to in the appended claims.

The invention is illustrated in the accompanying drawings, in which

Figure 1 is a front elevation of a sewing machine of the Union Special triple interlock type, and embodying my invention; Fig. 2 is a sectional view on line 2—2 of Fig. 1; Fig. 3 is a plan view of a portion of the working parts below the bed plate, illustrating the feeding mechanism; Fig. 4 represents in perspective the left hand portion of Fig. 1, showing a fabric in position to be sewed; Fig. 5 is a detached view of the auxiliary feed, and its supporting bar or frame; and Fig. 6 is a view similar to Fig. 2, showing means for adjusting the auxiliary feed.

In understanding these drawings, reference is made to the Union Special triple interlock machine, as illustrated in Patent 506,524, above referred to, and to patent to Muther & Dearborn, 299,568, of June 3, 1884, which latter illustrates the main feeding mechanism, my auxiliary feeding mechanism being used in conjunction therewith.

A represents the frame of the machine, which is of ordinary construction.

B is the main shaft, C the needle arm lever. D the needle bar actuated thereby, and a the looper co-operating with the needles to form stitches. Three needles b are used passing down through the fabrics three parallel rows of loops, which are secured on the under side of the fabric by the looper thread, thus uniting the abutting edges of two pieces

of fabric E and F, as shown in Fig. 5, of patent 506,525, above referred to.

G and H are oscillating thread carrying levers reciprocating back and forth across the line of the seam in front of the needles, so as to lay the threads which they carry, between the outer rows of stitches, the cross threads being bound both by said outer rows and the intermediate row.

10 The main feed dog I is carried upon an arm E', pivoted at one end to the upper portion of the rocking frame K, and resting at the other end upon the cam L, of the driving shaft B, and a downwardly depending piece E² secured to the arm E' projects beneath the cam L. All this is substantially the same as in Patent 299,568, the vertical movements of the feed dog carrying bar and feed dog I being effected by means of the cam L, and the horizontal movements by means of the jointed crank attachment and rocking frame, as shown also in said patent, or by means of the mechanism shown in patent issued to J. C. Goodwin, 517,141, March 27, 1894; the essential feature being the rocking frame to which the feed dog carrying bar is pivoted; the rocking frame having an oscillatory motion to draw the feed dog carrying bar back and forth horizontally, and 30 the feed dog carrying bar being raised up and down by the cam L.

Secured to the forward end of the feed dog carrying bar E' is a bracket or block N, having an ear or lug O projecting therefrom, into which is fastened a screw P, upon which is pivoted to one side the main feed dog, the auxiliary feed dog carrying bar Q; the feed dog c of which is herein shown as integral therewith. This feed dog carrying bar Q is in reality a pivoted lever and the pivot is below the plane of the feed dog, said bar or frame is bifurcated vertically adjacent its end opposite the feed dog, as at d and embraces the driving shaft B, or if desired a block or abutment may be placed on the driving shaft to be embraced by the fork. As the rocking frame E and arm E' therefore, move to impart the four motions to the main feed dog, it will be noticed that 50 the auxiliary feed dog carrying frame will swing on its pivot, and as shown it is so arranged that it will move ahead of, or faster than the main feed dog; thus when as shown in Fig. 4, it bears on a piece of fabric different from and abutting the fabric upon which the main feed dog bears, it will full or ruffle it more or less, as desired. That is as the main shaft B rotates, and the rocking frame and feed dog carrying bar are moved 55 by it; as the feed dog carrying bar moves back and forth horizontally, the main shaft, embraced by the fork on the auxiliary feed dog carrying frame, acts as an abutment to swing the said auxiliary feed dog carrying 60 frame on its pivot. It will thus be seen that

the main feed dog and the auxiliary feed dog receive their movement from the same point on the rocking frame, that is, the pivotal connection between the bar E and the frame K, which point is eccentric to the 70 pivotal support of the frame, and that I have also provided means for converting the movement of the rocking frame into a differential movement in the auxiliary feed dog relative to the main feed dog.

As a further and special improvement in a device of this kind, I have provided a means for adjusting the auxiliary feed in a vertical plane, whereby this feed may be thrown out of operation if not desired to 80 ruffle in one piece of fabric, or one side of a piece of fabric. This is illustrated in Fig. 6, in which upon the opposite side of the arm E' from that on which the auxiliary feed is supported, is pivoted at S an arm or lever R, 85 at its forward end carrying the screw P upon which the auxiliary feed is pivoted, while at the rear end, the lever R is adjustable up and down by the screw T, accessible through the cloth plate of the machine. By 90 turning out the screw T the front end of the auxiliary feed dog carrying frame may be lowered, so said feed dog will not come in contact with the work. It will also be noted that by adjusting the screw T, the pivot 95 screw P will be moved further from or nearer to the abutment engaging the bifurcated portion d of the feed bar or frame Q. Inasmuch as the pivot screw P moves in unison with the main feed bar and main feed dog, 100 the auxiliary feed dog will be given a greater or less movement relative to the main feed dog, accordingly, as the pivot screw is moved toward or away from the abutment. It will be seen, therefore, that 105 the fulling or ruffling action of the auxiliary dog may be varied and as above noted, the auxiliary dog may be rendered ineffective if the position thereof be changed by the screw T so that the movements of the auxiliary 110 dog are entirely below the cloth plate. It will of course, be understood that the auxiliary dog may be adjusted vertically so as to accomplish a variation in the throw thereof, 115 by reason of the fact that the presser foot is the usual yielding foot and will coöperate with said auxiliary dog in its various adjusted positions above the cloth plate.

I am aware that two motion feeds are not new, and that it has been heretofore proposed 120 in connection with an overseaming machine to provide a rocking frame having two rocking bars supported at different distances from the center of oscillation, one having a feed dog working in advance of the needle 125 and the other a feed dog working in rear of the needle, the one in front moving faster than the one in rear, the fabric ahead of the needle being puckered to prevent curling afterward, but the operation thereof is very 130

different from the present invention, in which one side of the fabric is ruffled or gathered to cause it to equal in width that portion of the fabric which is acted upon by the ordinary feed, thus giving it a ruffled or fulled appearance after sewing; that is in the present invention, as applied to the work of joining two pieces of fabric, only one fabric is ruffled or gathered, while the other portion is fed in the usual way. As far, however, as the mechanical operating parts are concerned, the manner of manipulating the auxiliary feed may be applied to a two motion feed technically so called, that is a two part feeding mechanism in which one portion moves faster than the other.

Having thus described my invention, what I claim and desire to secure by Letters Patent, is:

20. 1. A sewing machine including in combination a main feed bar, a feed dog carried thereby, means for operating said feed bar, an auxiliary feed dog, means for moving said auxiliary feed dog into and out of contact with the material during each feeding movement, means for giving said auxiliary feed dog a differential feeding movement, relative to the movement of said main feed dog, a pivoted lever, and means for swinging said lever about its pivot, whereby said relatively differential movement of the auxiliary feed dog may be rendered ineffective.

2. A sewing machine including in combination, a main feed bar, a feed dog carried thereby, means for operating said feed bar, an auxiliary feed dog, means for moving said auxiliary feed dog into and out of contact with the material during each feeding movement, means for giving said auxiliary feed dog a differential feeding movement relative to the movement of said main feed dog, a pivoted lever constructed to move bodily with said main feed bar and means for swinging said lever about its pivot, whereby said relatively differential movement of the auxiliary feed dog may be rendered ineffective.

3. A sewing machine including in combination a main feed dog, means for operating the same, an auxiliary feed dog, a feed bar supporting the same, means for moving the auxiliary feed dog into and out of contact with the material during each feeding movement, means for giving said auxiliary feed dog a differential movement relative to the main feed dog, and a lever operating through the auxiliary feed dog bar for moving said dog out of contact with the material, whereby its feeding action is rendered ineffective.

60. 4. A sewing machine including in combination, a main feed bar, a feed dog carried thereby, an auxiliary feed bar supported by said main feed bar and moving vertically in unison therewith, an auxiliary feed dog carried by said auxiliary feed bar, means for

giving the auxiliary feed dog a differential feeding movement relative to the feeding movement of the main feed dog, a pivoted lever moving bodily in unison with the main feed bar, and means for swinging said lever about its pivot, whereby said relatively differential feeding movement of the auxiliary feed dog, may be rendered ineffective.

5. A sewing machine including in combination, a rocking frame, a main feed dog, means for moving said main feed dog horizontally from said rocking frame, an auxiliary feed dog, means for giving said auxiliary feed dog a differential feeding movement from said rocking frame, a lever moving back and forth with said rocking frame, and connected to said auxiliary feed dog, whereby said auxiliary feed dog, may be moved out of contact with the material, and its feeding action rendered ineffective.

6. In a sewing machine, a driving shaft, a rocking frame, a main feed dog carrying bar pivoted thereto, a feed dog carried by said bar, a rocking feed dog carrying bar, pivoted to the main feed dog carrying bar, a feed dog carried by said rocking feed bar, said rocking feed dog being so disposed as to move in a plane parallel to the movements of the main feed dog, and means for oscillating said rocking feed dog bar on its pivot, whereby the rocking feed dog has a differential movement with respect to the main feed dog.

7. In a sewing machine, a driving shaft, a rocking frame, a main feed dog carrying bar pivoted thereto, a feed dog carried thereby, a rocking feed dog carrying bar, movable on the main feed dog carrying bar, said rocking feed dog and said main feed dog being constructed to move in parallel vertical planes and means for oscillating said rocking feed dog, whereby it has a differential movement with respect to the main feed dog.

8. In a sewing machine, a feeding device including a main feed dog carrying bar, and a feed dog supported thereon, an auxiliary feed dog pivotally attached at the forward end of said feed dog carrying bar said auxiliary feed dog and said main feed dog being constructed to move in parallel vertical planes, and means for imparting motion to the main feed dog carrying bar, and simultaneously imparting a differential motion to the auxiliary feed dog; substantially as described.

9. In a sewing machine, feeding mechanism including a main feed dog carrying bar, a feed dog carried thereby, a rocking frame on which said bar is pivoted, means for moving said main feed dog carrying bar, an auxiliary feed dog carrying bar pivoted to the forward end and to one side of the main feed dog carrying bar, a feed dog carried by said auxiliary feed bar, said auxiliary feed dog

- and said main feed dog being constructed to move in parallel vertical planes and means brought into operation by the operation of the main feed dog carrying bar for operating the auxiliary feed dog.
10. In a sewing machine having a main feed, an auxiliary feed pivoted thereto, a pivoted arm or lever carrying at one end the pivot upon which the auxiliary feed is 10 swung, and means for adjusting the opposite end of said pivoted arm or lever, whereby the auxiliary feed is raised and lowered; substantially as described.
11. In a sewing machine, a driving shaft, 15 a bar actuated thereby and carrying a member acting upon the fabric, a second bar carried by said first bar, and also carrying a second member acting upon the fabric but having differential movement with respect 20 to said first named member, an abutment, said bar carrying the second member having a rigid projection adapted in the bodily movement of the first bar to directly engage the abutment and thus impart said differential movement to the bar carrying the second member said member being so disposed 25 as to move in parallel vertical planes; substantially as described.
12. In a sewing machine, a driving shaft, 30 a bar actuated thereby and carrying a member acting upon the fabric, a second bar carried by said first bar, and also carrying a second member acting upon the fabric but having differential movement with respect 35 to said first named member, an abutment, said bar carrying the second member having a rigid projection adapted in the bodily movement of the first bar to directly engage the abutment and thus impart said differential movement to the bar or frame carrying 40 the second member, said members being so disposed as to move in parallel vertical lines, and means for adjusting the amount of reciprocal movement of the second bar.
13. In a sewing machine for uniting the edges of fabrics, stitch forming mechanism comprising a series of needles adapted to pass loops of threads down through the respective fabrics, complementary stitch forming mechanism, co-operating with the loops of thread upon the under side of the fabric and mechanism for uniting the rows of stitches upon the upper face of the fabric, a feeding mechanism co-operating with the 45 stitch forming mechanism, including a main feed dog and an auxiliary feed dog located side by side, said auxiliary feed dog being located in advance of the stitching point, and operating upon one piece of the fabric 50 only and moving in a vertical plane parallel with the plane of movement of the main feed dog, whereby one piece of fabric may be fed to the needle faster than the other fabric.
14. A sewing machine, comprising in combination, a cross stitch mechanism including a plurality of spaced needles, and mechanism co-operating therewith for making a cross stitch between certain of the rows of stitching, a feeding mechanism co-operating 65 with the stitch-forming mechanism including a main feed dog and an auxiliary feed dog located side by side, said auxiliary feed dog being located in advance of the stitching point, and operating upon one piece of 70 the fabric only and moving in a vertical plane parallel with the plane of movement of the main feed dog, whereby one piece of fabric may be fed to the needle faster than the other fabric.
15. A differential feeding mechanism including in combination a rocking frame, means for rocking said frame, a main feed dog, a main feed bar pivoted directly to said rocking frame, and supporting said main feed dog, an auxiliary feed dog, and means for operating said auxiliary feed dog from substantially the same point of connection with the rocking frame as the main feed bar, including devices for giving said auxiliary feed dog a differential movement 80 relative to the main feed dog.
16. A differential feeding mechanism including in combination a rocking frame, means for rocking said frame, a main feed 95 dog, a main feed bar pivoted directly to said rocking frame, and supporting said main feed dog, an auxiliary feed dog, and means for operating said auxiliary feed dog from substantially the same point of connection 100 with the rocking frame as the main feed bar, including devices for giving said auxiliary feed dog a differential movement relative to the main feed dog, and means whereby said differential movement may be varied.
17. In a sewing machine, a main shaft, a main feeding device including a main feed bar, a feed dog carried thereby, an auxiliary feeding device including a feed bar, a feed dog carried thereby, means for moving said 110 main feed dog and said auxiliary feed dog vertically substantially in unison, means for reciprocating the main feed bar and means for giving said auxiliary feed dog feeding movements, including a pivoted lever moving bodily in unison with the main feed bar, and devices co-operating with said lever for giving to said auxiliary feed dog, a differential movement relative to the main feed dog.
18. In a sewing machine, a main shaft, a main feeding device, including a main feed bar, a feed dog carried thereby, an auxiliary feeding device including a feed bar, a feed dog carried thereby, means for moving said 115 main feed dog and said auxiliary feed dog vertically substantially in unison, means for reciprocating the main feed bar, and means for giving to said auxiliary feed dog, a differential movement relative to the main feed dog.

for giving the auxiliary feed dog feeding movements, including a pivoted lever moving bodily in unison with the main feed bar, devices coöoperating with said lever for giving to said auxiliary feed dog a differential movement, relative to the main feed dog, and means for adjusting the position of said lever on its pivot, whereby the differential movement imparted to the auxiliary feed dog 10 may be varied.

19. In a sewing machine, a driving shaft, a rocking frame, a main feed dog carrying bar pivoted thereto, a feed dog carried thereby, an auxiliary feed dog carrying bar supported by the main feed dog carrying bar, an auxiliary feed dog carried thereby, means for operating said auxiliary feed dog carrying bar, from said rocking frame, and giving thereto a differential movement, relative 20 to the movement of the main feed dog, said means including a horizontally pivoted lever fulcrumed intermediate its ends, one end of said lever being connected to the auxiliary feed bar, and the other end of 25 said lever having means for adjusting said lever about its pivot, whereby the differential movement given to the auxiliary feed dog may be varied.

20. A sewing machine including in combination, a driving shaft, a main feed bar, a feed dog carried thereby, means for operating said main feed bar, an auxiliary feed dog and means for operating said auxiliary feed dog including a lever constructed 30 to move bodily in unison with the main feed bar, and means coöoperating with said lever for converting the movement thereof into a

differential movement in the auxiliary feed dog relative to the main feed dog.

21. A sewing machine including in combination a driving shaft, a main feed bar, a feed dog carried thereby, means for operating said main feed bar, an auxiliary feed dog and means for operating said auxiliary feed dog, including a lever constructed 40 to move bodily in unison with the main feed bar, and means coöoperating with said lever for converting the movement thereof into a differential movement in the auxiliary feed dog, relative to the main feed dog, and 45 means for adjusting said lever whereby said relatively differential movement may be varied and also rendered ineffective.

22. A differential feeding mechanism including in combination a rocking frame, a 50 pivot on which said frame is mounted, means independent of said pivot for rocking said frame, a main feed dog, an auxiliary feed dog, means for operating said feed dogs, including devices for giving the auxiliary 55 feed dog a differential movement relative to the main feed dog, said means comprising a bar supporting both dogs, said means being actuated from the same pivotal point on the rocking frame, which point is located 60 eccentrically to the pivot upon which the rocking frame moves.

In testimony whereof I affix my signature, in presence of two witnesses.

Correction in Letters Patent No. 901,792.

It is hereby certified that in Letters Patent No. 901,792, granted October 20, 1908, upon the application of Ernest Frederick Durand, of Paris, France, for an improvement in "Feeding Mechanism for Sewing-Machines," an error appears in the printed specification requiring correction, as follows: In line 49, page 1, the word "pulled" should read "fullled"; and that the said Letters Patent should be read with this correction therein that the same may conform to the record of the case in the Patent Office.

Signed and sealed this 17th day of November, A. D., 1908.

[SEAL.]

C. C. BILLINGS,

Acting Commissioner of Patents.

for giving the auxiliary feed dog feeding movements, including a pivoted lever moving bodily in unison with the main feed bar, devices coöoperating with said lever for giving to said auxiliary feed dog a differential movement, relative to the main feed dog, and means for adjusting the position of said lever on its pivot, whereby the differential movement imparted to the auxiliary feed dog 10 may be varied.

19. In a sewing machine, a driving shaft, a rocking frame, a main feed dog carrying bar pivoted thereto, a feed dog carried thereby, an auxiliary feed dog carrying bar supported by the main feed dog carrying bar, an auxiliary feed dog carried thereby, means for operating said auxiliary feed dog carrying bar, from said rocking frame, and giving thereto a differential movement, relative 20 to the movement of the main feed dog, said means including a horizontally pivoted lever fulcrumed intermediate its ends, one end of said lever being connected to the auxiliary feed bar, and the other end of 25 said lever having means for adjusting said lever about its pivot, whereby the differential movement given to the auxiliary feed dog may be varied.

20. A sewing machine including in combination, a driving shaft, a main feed bar, a feed dog carried thereby, means for operating said main feed bar, an auxiliary feed dog and means for operating said auxiliary feed dog including a lever constructed 30 to move bodily in unison with the main feed bar, and means coöoperating with said lever for converting the movement thereof into a

differential movement in the auxiliary feed dog relative to the main feed dog.

21. A sewing machine including in combination a driving shaft, a main feed bar, a feed dog carried thereby, means for operating said main feed bar, an auxiliary feed dog and means for operating said auxiliary feed dog, including a lever constructed 40 to move bodily in unison with the main feed bar, and means coöoperating with said lever for converting the movement thereof into a differential movement in the auxiliary feed dog, relative to the main feed dog, and 45 means for adjusting said lever whereby said relatively differential movement may be varied and also rendered ineffective.

22. A differential feeding mechanism including in combination a rocking frame, a 50 pivot on which said frame is mounted, means independent of said pivot for rocking said frame, a main feed dog, an auxiliary feed dog, means for operating said feed dogs, including devices for giving the auxiliary 55 feed dog a differential movement relative to the main feed dog, said means comprising a bar supporting both dogs, said means being actuated from the same pivotal point on the rocking frame, which point is located 60 eccentrically to the pivot upon which the rocking frame moves.

In testimony whereof I affix my signature, in presence of two witnesses.
